UNITED STATES PATENT OFFICE.

OLIVER M. EDWARDS, OF SYRACUSE, NEW YORK

WINDOW.

No. 902,060.

Specification of Letters Patent.

Patented Oct. 27, 1908.

Application filed January 5, 1906. Serial No. 294,706.

To all whom it may concern:

Be it known that I, OLIVER M. EDWARDS, a citizen of the United States, residing at Syracuse, county of Onondaga, State of New York, have invented certain new and useful Improvements in Windows, of which the following is a full, clear, and exact description, reference being had to the drawings accompanying the same.

My invention relates generally to windows wherein sash supporting or counterbalancing means are employed to more or less support the sash; and it has for one of its objects to provide sash holding means adapted to remain more or less in continuous holding contact and connections between such holding means and the sash supporting or counterbalancing means.

Another object is to provide sash holding means in the form of a lever or levers and connections between such holding means and the sash supporting and counterbalancing means.

Another object is to provide sash holding means adapted to be mounted on the sash and engage with the frame of the window at opposite sides thereof and connections between the supporting and holding means.

Another object is to provide sash holding means adapted to be mounted on the sash and having stop or buffer devices attached thereto adapted to arrest the movement of the sash in the opening direction.

Other objects will appear from the descriptions hereinafter given; and my invention consists in the combinations of parts, devices or members hereinafter set forth and particularly pointed out in the claims hereunto annexed, which form a part of this specification.

Like letters of reference, wherever they occur, indicate corresponding parts in the several figures of the drawings.

Figure 1 shows in front elevation one embodiment of my invention. Fig. 2 is a vertical sectional view of what is seen in Fig. 1 on line 2—2 thereof. Fig. 3 is a cross sectional view on line 3—3 of Fig. 1. Fig. 4 is a cross sectional view on line 4—4 of Fig. 1. Fig. 5 is a front elevation of one side of a window and its sash showing another embodiment of my invention wherein a web of cloth and metal bar are employed to connect the sash holding means to the spring

roller, as there shown. Fig. 6 is a vertical 55 sectional view, on line 6—6 of Fig. 5, showing the manner in which the usual metal bar, as seen in Fig. 5, may be connected with the sash holding means attached to the sash. Fig. 7 shows in side elevation a portion of a 60 sash with a modified form of sash holding means applied thereto. Fig. 8 shows in front elevation portions of a sash having another modified form of holding means mounted thereon. Fig. 9 shows in side elevation 65 that which is seen in Fig. 8 with the window frame in section.

In Figs. 1 to 3, inclusive, A represents the window frame, B, the sash, movable in the guideway a, formed in the frame A, and B' is 70 a supplemental sash fixedly secured in the frame above the sash B. R represents a spring roller which may be of the usual construction, so commonly used at the present time for supporting and more or less counter- 75 balancing sashes, (as for instance in railway cars,) such roller being mounted in any desired manner in or on the window frame A to so support or balance sash B. Attached to this roller R, at its opposite ends, as shown, 80 is a chain, cord or other flexible material r, which passes from one end of such roller, as seen at the right of Fig. 1, downwardly and around a stud c, of suitable construction mounted on one end of the pivoted lever C of 85 sash holding means D, which in turn is secured to the sash A near its upper right hand corner, thence along and near the top portion of such sash to and around a similar stud c' mounted on pivoted lever C' of sash holding 90 means D', attached to sash A near its upper left hand corner, thence upwardly to roller R to which it is secured near its left hand end. This chain r is free to slide or move on studs c and c', or on either of such studs, so that the 95 weight of the sash is about equally distributed on this chain, cord or other flexible material, and the sash is about equally supported by both side portions of the window frame. As a result the levers C and C' are made to bear 100 upon the opposite sides of the window frame with substantially an equal pressure to hold the sash in the frame against rattling and to prevent the free passage of air and dirt past the side edges of the sash. As here shown 105 the ends of these levers, which bear against the frame, are beveled and bear against beveled surfaces formed upon the opposite sides

of the window frame. As a result of this the sash is forced in two directions in a well known manner. These levers with their connections to the sash form sash holding means, D and D'.

As the roller R turns in its mountings on the frame A the chain or other flexible material winds or unwinds therefrom and the sash B may be correspondingly raised or lowered the same as if such chain or flexible material were secured directly to the sash as seen in prior patent No. 681,688 dated Sept. 3, 1901. As here shown this chain or flexible material is indirectly connected with the sash by being passed over the studs c and c' attached to levers C and C', respectively, so that the weight of the sash is exerted on said chain or material to move such levers on their pivots and consequently move the opposite ends of such levers into close and intimate contact with beveled surfaces b and b' of the guideway a formed in the frame A. The guideway a is clearly seen in cross section in Fig. 3, where the lever C' is shown in engagement with the beveled surface b', there being a similar surface on the opposite side of the frame A for the end of lever C to bear against, which is designated as b.

Whenever the sash B is lifted, so as to release the material r and the roller R of its weight, such roller winds up, if unrestrained, and, if the sash is underbalanced by such roller, the levers, as C and C', are not forced against the beveled surfaces b and b' to such an extent as when the sash is fully balanced and such sash is not held in its frame as tightly and consequently may be lifted with a less expenditure of force by reason of the lesser stress of the spring in the roller and of the consequent lessened holding action of these levers, (of these sash holding means, as D and D',) on the window frame. The angle that these levers C and C' are arranged at relatively to the window frame is such that the levers tend to move away from the frame as the window is lifted, to open such window, and yet is also such that the ends of these levers may remain in contact with the window frame as the sash is moved in the closing direction without unduly engaging therewith and materially affecting such closing movement. Thus the sash may be moved in both directions with these levers, as C and C', in continuous frictional contact with such window frame, with the spring roller, as R, exerting its full force upon such levers in partially supporting such sash. This is also the case both normally and while opening and closing the window. From this it will be seen that these sash holding means are more or less in continuous frictional contact with the beveled surfaces, as b and b', of the guideway, formed in the frame A.

As here shown, additional sash holding means, as D² and D³, are secured to the lower

portion of the sash B, as seen in Figs. 1 and 4. As here shown each of these sash holding means, as D² and D³, is provided with a sliding bolt, as d and d', respectively, which is provided with a beveled engaging end to engage with the beveled surfaces, as d² and d³, (see Fig. 4,) respectively. Each bolt is spring pressed into contact with its correspondingly beveled surface of the guideway in a well known manner and such bolts are moved against the stress of their springs by levers, as d⁴ and d⁵, respectively, as will be readily understood from the drawings herein.

Each of the sash holding means, as D, D', D² etc., act independently of each other in holding the sash in its guideway and to substantially the same extent at opposite sides of the sash, because the force exerted by the spring roller and the springs acting on the sliding bolts tend to equalize and force the sash edgewise until substantially an equal result is reached at each of both edges thereof.

To open and close the window the levers, controlling the sliding bolts, as d and d', of holding means, as D² and D³, are manipulated in a well known manner and the sash is relieved, in whole or in part, from their holding action. With the sash thus relieved and the application of still more force in the same direction to such levers the sash is moved in the opening direction, then without releasing the levers and applying force to the thumb pieces in the opposite direction the sash is moved in the closing direction. Upon the release of these sliding bolts, as d and d', the frictional contact of such bolts and the levers, as C and C', may be such as to hold the sash in the desired position, even when some considerable force is applied thereto. When the sash is about balanced by the spring in the roller R the holding action of the levers, as C and C', of the holding means D and D' may be sufficient to hold the sash in any desired position in the guideway and prevent its moving therein without force being applied thereto to overcome the frictional contact of the holding means D and D' on the opposite sides of the frame.

If the sash be underbalanced the sliding bolts, as d and d' of holding means D² and D³, may be made to engage with recesses suitably formed in the beveled surfaces as in practice is quite commonly done at the present day and thus be held in the open position, and if over balanced these bolts may engage with suitable recesses or abutments to hold the sash in the closed position, also as is quite commonly done as desired. Instead of arranging these levers of these sash holding means D and D', as shown in Figs. 1 to 3, inclusive, they may be arranged as seen in Figs. 5 to 7, inclusive, where they take on the form of rock shafts, as there seen. As seen in Figs. 5 and 6 these rock shafts, (one only being shown the other being substantially a

duplicate, but left hand instead of right,) as C², is provided with two arms, as c² and c³, one of which, as c², is provided with an oblong opening or recess to receive, as there shown, 5 one end of the flat bar of metal in an end-wise direction, which bar is quite commonly used in connection with a band of flexible material for connecting spring rollers with sashes. This bar r² passes through a hem or 10 pocket in the lower portion of the web of flexible material, as r², and one end is received by the oblong opening or recess of the sash holding means at one side of the window and the other end of such bar passes through 15 a similar opening or recess in one arm of the rock shaft at the other side or edge of the window, as will be readily understood by those skilled in the art of windows.

The force of the spring of roller R' is exerted on the arms, as c², of these rock shafts, 20 through the web r² and the metal bar r³, and tends to rock such shafts in their bearings, as I, which are secured to the sash B² as shown. This sash B² is adapted to move up 25 and down in the guideway formed in the frame A'. The other arms of each of these rock shafts, as c³, rests or frictionally bears against the inner side portion of the guideway on opposite sides of the window so as to 30 force the sash against the opposite or outer side portion thereof, as is clearly seen in Fig. 6. These arms, as c² and c³ are arranged, as here shown, at nearly right angles to each other and consequently force exerted in an 35 upward direction on arm, as c², tends to force arm, as c³, laterally, which in turn tends to force the sash laterally, in the opposite direction. If desired these arms, as c³, may be provided, as seen in Fig. 6 with stop or buffer 40 portions, as x, designed to contact with portions of the window frame, as x', on the opening of the window to its full extent. If this construction of rock shaft and buffer extension, as x, to the arm, as c³, is used in the construction of window frame seen in Figs. 1 to 45 3, then such portions, as x, of these arms, as c³, would contact with that portion of the window frame just below the spring roller, seen in Fig. 2, which is a common form of car construction at the present time. Instead of arranging these rock shafts as seen in Figs. 5 and 6 they may be arranged as seen in Fig. 7, or as seen in Figs. 8 and 9 of the drawings. 50 In either case the mode of operation of the rock shafts is the same, so far as concerns the holding of the sash in the frame and the action of the buffer portions of such rock shafts, as will be manifest to a mechanic. In each construction of parts seen in these 55 Figs. 5 to 9, inclusive, the rock shafts are arranged with their arms within the space forming the guideway in which the sash moves in opening and closing the window and those portions of the sash to which the 60 rock shafts are attached are moved laterally 65

or at substantially right angles to the direction in which the sash moves in opening and closing the window.

In Fig. 7 the arms, as c⁴ and c⁵ of the rock shaft C⁴ are arranged to move the sash in 70 the opposite direction to that in which the sash is moved in Figs. 5 and 6. The arm c⁵ of this rock shaft C⁴, in Fig. 7, is provided with a stud c⁶ around which a chain, cord or other flexible material may pass, in the manner indicated in Fig. 8, the action of which on the rock shaft is the same as is that of the web or other flexible material on the rock shafts in the construction illustrated in Figs. 5 and 6. The upper portions of surfaces x² 80 of these arms c⁴ of the rock shaft C⁴ serves the same purpose in the same way in the form and arrangement seen in Fig. 7 as is served in the form and arrangement of rock shaft arms seen in Figs. 5 and 6.

A somewhat different form and arrangement of rock shaft arms is shown in Figs. 8 and 9 than is seen in Figs. 5 to 7, inclusive. In Figs. 8 and 9 the rock shaft arms, as c⁸ and c⁹, of rock shafts C⁸ are arranged to force the sash toward the exterior portion of the guideway in which the sash moves and a separate arm, as x³, carries the buffer surface which is to abut against a portion of the frame in which the sash moves to protect the sash supporting means, (when in the form of a spring roller mounted directly over the upper portion of the sash,) from injury arising from the sash striking such means in the opening of the window. The operation of these buffer portions of the rock shafts is the same in any one of the forms and arrangement of arms of the rock shafts that are herein shown. These rock shafts C⁸ are preferably mounted on the top edge of the sash B⁶ and they are arranged at opposite edge portions thereof to bear against opposite side portions of the window frame A⁶, as shown. The arms, as c⁹, of these rock shafts C⁸ are each provided with studs, as c¹⁰, which studs are 100 provided with headed portions to hold the chain, cord or other flexible material attached to a spring roller or other balancing or sash supporting device or devices from slipping off the ends of such studs, the body 105 of the arms, as c⁹, holding such chain, cord etc from slipping off in the other direction.

A chain, as seen in Figs. 1 and 2, having its opposite ends secured near to the opposite ends of a spring roller, as there seen or otherwise, may be employed in the construction seen in Figs. 8 and 9 if desired. As shown in Fig. 8 the chain, cord or other flexible material, as r⁶, passes from sash supporting device or devices down and around one stud, as c¹⁰, thence along toward and around the other stud, as c¹¹, and thence to the sash supporting device or devices again.

When studs like those herein shown are employed, in connection with the lever por- 110 115 120 125 130

tions of sash holding means, as the means for connecting the sash supporting means with the sash holding means the connection between the supporting and holding means is 5 readily made and unmade, whether such supporting means include chains, cords etc., as herein shown or some other form of material which can be readily hooked over and readily unhooked from such studs. These 10 studs form a convenient form of connecting means between the supporting and holding means and their use as herein set forth will naturally suggest the use of other means by which the same work may be done in sub- 15 stantly the same way to accomplish essentially the same result. As here shown, the flexible material of the sash supporting means is readily moved relatively to the sash holding means by applying a sufficient 20 force thereto to overcome the force exerted by the supporting means and when this is done such material can be readily slipped or hooked over such stud or studs and also readily slipped off or unhooked therefrom. 25 In the several forms of sash holding means herein shown, wherein levers are employed, it is preferable that the angles, at which the arms of such levers are arranged, (which bring pressure to bear to hold the sash in its 30 frame) relatively to the side portions of the frame, be such that about the same force be exerted by such levers on the frame in both directions of movement of the sash, in opening and closing the window. The several 35 forms herein shown having their lever portions connected to the sash supporting means are convenient forms and are well adapted to do the work they are designed to accomplish and these forms will naturally 40 suggest other forms which will have substantially the same coactive relations with the other parts employed in making up the combinations of members or elements herein- after particularly pointed out. 45 In each embodiment of this invention herein shown and described the mode of operation is such that the sash holding means, having these lever portions connected with the sash supporting means, are continuously 50 acting to more or less hold the sash in the guideway, whether the window be closed or is being opened or closed. This prevents the sash from suddenly and quickly falling, when the window is open, and lessens the dangers 55 arising from such accidental falling of window sashes.

Other forms of sash holding means, as D^2 and D^3 , or other desirable forms, may be employed to aid the sash holding means, 60 having the lever portions, to firmly hold the sash in its frame with great advantage, whether it be when the window is closed or is open. When such other forms are thus employed it is preferable that each such 65 means should be provided with manually

operable parts which are operated when the window is to be opened or closed to partially release the sash in its guideway.

What I claim as new is:—

1. In a window the combination, substantially as set forth, of a frame adapted to receive and hold a sash, a sash movable in the frame, sash holding means consisting in part of a lever pivotally mounted on the sash, and sash supporting means engageable with such lever at an angle to the direction of movement of the sash in the frame and at the same time adapted to more or less support the sash. 70

2. In a window the combination, substantially as set forth, of a frame adapted to receive and hold a sash, a sash movable in the frame, sash holding means mounted on the sash, sash supporting means, and means connecting the sash holding means and supporting means together and permitting of movement of a portion of one relatively to a portion of the other, whereby a movement of one means relatively to the other may take place and thereby enable the supporting 80 means to evenly support or carry the sash. 85

3. In a window the combination, substantially as set forth, of a frame adapted to receive and hold a sash, a sash movable in the frame, holding means arranged at each of two edge portions of the sash, a support for the sash having a part composed of flexible material connecting the holding means at opposite edge portions of the sash together, whereby the sash is held in the frame with 95 substantially equal force at its opposite edges. 100

4. In a window the combination, substantially as set forth, of a frame adapted to receive and hold a sash, a sash movable in the frame, a pair of oppositely arranged sash holding levers, sash supporting means, and means detachably connecting such holding levers to the supporting means, whereby, the sash supporting means act upon the sash 105 through the holding levers to support the sash and hold it in the frame and are detachable from the sash without disturbing the fastenings which secure the holding levers to the sash. 110

5. In a window the combination, substantially as set forth, of a frame adapted to receive and hold a sash, a sash movable in the frame, sash supporting means connectible with the sash, and means, portions of which 115 are attached to the sash and provide recesses opening towards one another and adapted to receive the opposite ends of a bar in an end-wise direction, whereby, the sash supporting means are detachable from the sash without disturbing the fastenings which secure such portions to the sash. 120

6. In a window the combination, substantially as set forth, of a frame adapted to receive and hold a sash, a sash movable in the 125

frame, sash holding levers mounted on the sash, sash supporting means provided with a web of flexible material, and a bar detachably connecting portions of such web with the holding levers, whereby, the supporting means are detachable from the holding levers without disturbing the fastenings which secure the levers to the sash.

7. In a window the combination, substantially as set forth, of a frame adapted to receive and hold a sash, a sash movable in the frame, a rock shaft mounted on the sash, an arm of which is adapted to bear against the frame to hold the sash therein, and means engageable with the rock shaft adapted to move and hold its bearing arm in bearing position against the frame, whereby a portion of the sash is held to exclude dirt and drafts of air by the engagement of the arm of the 20 rock shaft with the frame.

8. In a window the combination, substantially as set forth, of a frame adapted to receive and hold a sash, a sash movable in the frame, a rock shaft mounted on the sash substantially within the space in which the sash

moves to open and close the window having an arm adapted to bear against the frame to force a portion of the sash into engagement with an opposite portion thereof to exclude dirt and drafts of air, and means engageable 30 with the rock shaft adapted to move and hold it and its bearing arm in position against the frame.

9. In a window the combination, substantially as set forth, of a frame adapted to receive and hold a sash, a sash movable in the frame, a plurality of rock shafts mounted on the sash, an arm of each of which is adapted to bear against the frame to hold the sash therein, and means engageable with each 35 rock shaft adapted to move and hold it and its bearing arm in bearing position against the frame, whereby a portion of the sash is held to exclude dirt and drafts of air by the engagement of such arms with the frame.

OLIVER M. EDWARDS.
